Primary Examiner — Bridget L Eland(74) *Attorney, Agent, or Firm* — FisherBroyles, LLC;
 Craig W. Mueller(57) **CLAIM**

The ornamental design for a tissue specimen marking clip, as shown and described.

DESCRIPTION

FIG. 1 is a perspective view of a tissue specimen marking clip showing the new design;

FIG. 2 is a top plan view thereof; and,

FIG. 3 is a left elevation view thereof, the right elevation view being a mirror image thereof.

1 Claim, 3 Drawing Sheets(56)
